UNITED STATES PATENT OFFICE.

VINCENT BENDIX, OF CHICAGO, ILLINOIS.

ENGINE STARTER.

Application filed May 29, 1917. Serial No. 171,787.

My invention relates to that type of engine starter and to the transmission or drive portion thereof as exemplified in general by patents heretofore issued to me, for 5 instance, Patent No. 1,172,864, dated February 22, 1916, which starter is characterized by a prime mover such as an electric motor and a transmission or drive connected therewith either directly or indirectly for transmitting the power of the motor by means 10 of a rotatable shaft such as a screw shaft and a driving member, such as a pinion, mounted thereon and adapted to operatively engage a part of the engine to be started, 15 such as the fly wheel thereof.

The object of my present invention is to produce a drive of this general type but of somewhat different construction and functioning and made efficient and compact and 20 providing a driving member or pinion which is enabled to be of comparatively small diameter and a control member mounted on the shaft for longitudinal and rotary movements and adapted to impart its movements 25 to the driving member preferably through a yielding driving connection, such as a spring.

In the drawing Fig. 1 is a sectional elevation of a drive embodying my invention 30 and illustrating a portion of the fly-wheel of the engine and of the starting motor; Fig. 2 a section on the line 2—2 of Fig. 1; and Fig. 3 a sectional elevation of a modified form of construction.

Referring to the embodiment of my invention as shown in Figs. 1 and 2, the starting motor, indicated at A, is provided with 35 an extended armature shaft which may be considered the driving shaft, here shown as made in two separate detachable parts and connected directly with the drive or transmission about to be described. In the present instance the inner part 1 is a plain shaft and the outer part 2 a screw shaft, which is secured in suitable manner to the 40 outer end of the plain shaft as by means of its screw-threaded portion screwing into the end bore 1^a of the latter shaft, a suitable hardened washer 3 being preferably interposed between an intermediate shoulder of 45 the screw shaft and the outer end of the plain shaft, to act as a stop for the screw member in its longitudinal movement on the screw shaft towards the left. It is obvious 50 that the two shafts might be made integral but by preference they are made in two de-

tachable parts as shown, particularly because the drive is made and sold separately to be applied to starting motors whose armature shaft has been made adapted by 60 the manufacturers thereof to take such drive. Consequently, in the broader aspect of my invention the driving shafts 1 and 2 may be considered as one and the same. The screw shaft is provided with a screw- 65 threaded portion 2^b extending nearly to the outer end thereof and on these threads is mounted, by being screw-threaded thereon, a screw member 4 which by reason of its mounting is capable of longitudinal and rotary movement with respect to the screw shaft and also rotary movement therewith. The screw threads are abruptly stopped at 70 their outer ends to form stops for the outward travel of the screw member. At the 75 inner end of its limit of travel it is stopped by the washer 3.

The screw member which in its broad significance is a control member, is operatively connected to a driving member or pinion 80 5 by a suitable driving means which is here shown as a yielding driving connection in the form of a coiled spring 6 connected respectively to the screw-member and driving member. One end of the spring is anchored 85 to a stud 7 screwing into the screw member and the other end to a stud 8 screwing into the driving member.

The driving member 5 has teeth at its inner end adapted to mesh with the teeth 9^a of the 90 fly-wheel 9 of the engine to be started. This driving member or pinion is capable of both longitudinal movement and rotary movement with respect to the screw shaft and also rotary movement therewith and is controlled 95 by the screw member so that it partakes of substantially the same movements thereof. As shown, the driving member is mounted upon the shaft 1, being adapted to slide thereon and having rotary movement thereof 100 and therewith, inasmuch as it is indirectly connected thereto through the screw shaft, screw member and spring. The provision of the anchoring studs on one side of the driving head and pinion serves to overbalance these 105 parts, to thereby weight them on one side and thereby cause a clutching through centrifugal forces when demeshing but this feature is immaterial in so far as my invention viewed in its broader aspect is concerned.

The outer portion of the driving member is formed as a cylindrical extension or hub

5^a between which and a similar hub 4^a on the screw member is a clearance or compression space 10, with the result that in the event that the pinion teeth should abut the fly-wheel 5 teeth end to end, the pinion will yield outwardly longitudinally with respect to the screw member as permitted by the spring coils. In order to bridge this space and prevent the possibility of a coil dropping or 10 wedging thereinto, when such spring is wound or under tension during the driving operation or by reason of back fires of the engine, suitable means are provided, such as a sleeve 11 secured to the hub 4^a and having a 15 sliding fit upon the hub 5^a.

Describing the operation of the drive, and starting with the parts in their normal position shown, the rotation of the screw shaft by the rotation of the electric motor causes the 20 screw member 4 to move inwardly longitudinally, that is towards the left in Fig. 1, carrying with it the driving member 5 and causing the latter to mesh with the fly-wheel. When the screw-member contacts the washer 25 3 it is at its limit of travel in this direction and thereupon such screw-member and consequently the pinion or driving member will be rotated, thereby driving the fly-wheel. The power is transmitted from the screw 30 member to the pinion through the coiled spring 6. When the engine has started on its own power, the accelerated movement of its fly-wheel will automatically demesh the driving member and cause the same to be moved 35 back to normal or home position through the control thereof by the screw member. The movement of the screw member in this direction is limited by the end of the screw threads on the screw shaft.

40 In Fig. 3 I have shown a modified form of construction in which the corresponding parts are similarly numbered. According to this construction the driving shaft which is made in two parts has its innermost part or 45 member a screw shaft 12 and its outer part the plain portion 13. In the form shown in Fig. 1 the driving member or pinion 5 moved inwardly toward the motor when the drive was operated, but in Fig. 3 such driving member moves in the opposite direction, that is, 50 away from the motor when going into mesh with the fly-wheel. In other respects the operation is the same.

I do not herein claim the special features 55 of the drive of Fig. 3, but have made the same the subject matter of an application filed by me on August 13, 1917, Serial No. 185,873, which has since issued as Patent No. 1,551,787, dated September 1, 1925.

60 I claim:

1. A drive for engine starters comprising a rotatable shaft, a driving member mounted thereon for both longitudinal and rotary movement thereof and rotary movement therewith and adapted to cooperate with

and drive a member of the engine to be started, a control member mounted on said shaft for longitudinal and rotary movement thereof and rotary movement therewith, and driving means between the driving member and the control member. 70

2. A drive for engine starters comprising a rotatable shaft, a driving member mounted thereon for both longitudinal and rotary movement 75 thereof and rotary movement therewith and adapted to cooperate with and drive a member of the engine to be started, a control member mounted on said shaft for longitudinal and rotary movement thereof and rotary movement therewith, and a yielding driving means between the driving member and the control member. 80

3. A drive for engine starters comprising a rotatable shaft, a driving member mounted thereon for both longitudinal and rotary 85 movement thereof and rotary movement therewith and adapted to cooperate with and drive a member of the engine to be started, a control member mounted on said shaft for longitudinal and rotary movement thereof and rotary movement therewith, and a spring 90 driving connection between the driving member and the control member.

4. A drive for engine starters comprising a rotatable shaft having a screw-threaded portion, a driving member mounted thereon for both longitudinal and rotary movement thereof and rotary movement therewith and adapted to cooperate with and drive a member of the engine to be started; a screw member 95 mounted on the threaded portion of the shaft, and a driving connection between said driving member and screw member. 100

5. A drive for engine starters comprising a rotatable shaft, having a screw threaded portion a driving member mounted thereon for both longitudinal movement thereof and rotary movement therewith and adapted to cooperate with a member of the engine to be started; a screw member mounted on the 105 threaded portion of the shaft, and a yielding driving means between said driving member and screw member. 110

6. A drive for engine starters comprising a rotatable screw shaft, a driving member 115 mounted for longitudinal movement with relation to the shaft and rotary movement therewith, a screw member mounted on said shaft and controlling the relative movements of the driving member, and a driving means 120 between said screw member and driving member.

7. A drive for engine starters comprising a rotatable shaft having a screw-threaded portion, a driving member mounted thereon for both longitudinal movement thereof and rotary movement therewith and adapted to cooperate with and drive a member of the engine to be started; a screw member mounted 125 on the threaded portion of the shaft, for 130

- longitudinal and rotary movement thereof and rotary movement therewith, and a driving means between said driving member and screw member.
5. 8. A drive for engine starters comprising a rotatable shaft having a screw-threaded portion, a driving member mounted for both longitudinal movement thereof and rotary movement therewith and adapted to cooperate with and drive a member of the engine to be started; a screw member mounted on the threaded portion of the shaft for longitudinal and rotary movement thereof and rotary movement therewith, and a driving 10 means between said driving member and screw member.
9. A drive for engine starters comprising a rotatable shaft, a driving member mounted thereon for both longitudinal movement 20 thereof and rotary movement therewith and adapted to cooperate with and drive a member of the engine to be started, a control member mounted on said shaft for longitudinal and rotary movement thereof and rotary movement therewith, means for stopping the said longitudinal movement of the control member, and driving means between the driving member and the control member.
10. A drive for engine starters comprising a rotatable screw shaft, a pinion capable of rotary and longitudinal movements, a screw member screw threaded on the shaft for rotary movement therewith and longitudinal movement thereof and controlling the movements of the pinion, and a driving means between said member and pinion.
11. A drive for engine starters comprising a rotatable screw shaft, a pinion capable of rotary and longitudinal movements, a screw member screw threaded on the shaft for rotary movement therewith and longitudinal movement thereof and controlling the movements of the pinion, and a yielding driving means between said member and pinion.
12. A drive for engine starters comprising a rotatable screw shaft, a pinion capable of rotary and longitudinal movements, a screw member screw threaded on the shaft for rotary movement therewith and longitudinal movement thereof and controlling the movements of the pinion, and a spring connected with said member and pinion respectively and forming a yielding driving means therebetween.
13. A drive for engine starters comprising a rotatable screw shaft, a pinion capable of rotary and longitudinal movements, a screw member screw threaded on the shaft for rotary movement therewith and longitudinal movement thereof and controlling the movements of the pinion, a driving connection between said member and pinion, in combination with a driving shaft to which said rotatable shaft is secured and on which said driving member is mounted.
14. A drive for engine starters comprising a rotatable driving shaft made in two parts detachably connected together in alinement, one being a screw shaft and the other a plain shaft, and engine driving mechanism mounted on the driving shaft and actuated thereby and having portions for coaction with each of said shaft-parts.
15. A drive for engine starters comprising a rotatable driving shaft made in two parts 75 detachably connected together in alinement, the outer one being a screw shaft and the inner one a plain shaft, and engine driving mechanism mounted on the driving shaft and actuated thereby and having threaded and 80 plain portions coacting respectively with the outer and inner parts of said shaft.
16. A drive for engine starters comprising a rotatable driving shaft made in two parts detachably connected together in alinement, 85 one being a screw shaft and the other a plain shaft, a driving member mounted on the plain shaft, a screw member mounted on the screw shaft, and a driving connection between the two members.
17. A drive for engine starters comprising a rotatable driving shaft made in two parts detachably connected together in alinement, one being a screw shaft and the other a plain shaft, a driving member mounted on the 95 plain shaft, a screw member mounted on the screw shaft, and a yielding driving means connecting between the two members.
18. A drive for engine starters comprising a rotatable driving shaft made in two parts 100 detachably connected together in alinement, one being a screw shaft and the other a plain shaft, a driving member mounted on the plain shaft, a screw member mounted on the screw shaft for longitudinal movement thereof and 105 rotary movement therewith, means for stopping such longitudinal movement, and driving means connecting between the two members.
19. A drive for engine starters comprising a rotatable driving shaft made in two parts 110 detachably connected together in alinement, one being a screw shaft and the other a plain shaft, a driving member mounted on the plain shaft, a screw member mounted on the screw 115 shaft for longitudinal movement thereof and rotary movement therewith, means for stopping such longitudinal movement consisting of a projection at the point of connection of said two parts, and driving means connecting 120 between the two members.
20. A drive for engine starters comprising a rotatable driving shaft made in two parts detachably connected together in alinement, one being a screw shaft and the other a plain 125 shaft, a driving member mounted on the plain shaft, a screw member mounted on the screw shaft for longitudinal movement thereof and rotary movement therewith, means for stopping such longitudinal movement consisting 130

- of a washer at the point of connection of said two parts, and driving means connecting between the two members.
21. A drive for engine starters comprising a rotatable screw shaft, a pinion capable of rotary and longitudinal movements, a driving head screw-threaded on the shaft for rotary movement therewith and longitudinal movement thereof and controlling the movements of the pinion, a driving connection between said member and pinion, in combination with a driving shaft which has a screw threaded bore at its outer end and on which said driving member is mounted, said screw shaft having an end screw-threaded to fit in said bore.
- 15 22. A drive for engine starters comprising a rotatable screw shaft, a pinion capable of rotary and longitudinal movements, a driving head screw-threaded on the shaft for rotary movement therewith and longitudinal movement thereof and controlling the movements of the pinion, a driving connection between said member and pinion, in combination with a driving shaft which has a screw-threaded bore at its outer end and on which said driving member is mounted, said screw shaft having an end screw-threaded to fit in said bore, and a washer interposed at the point of connection of the two shafts.
- 30 23. A drive for engine starters comprising a rotatable screw shaft, a pinion capable of rotary and longitudinal movements, a screw member screw-threaded on the shaft for rotary movement therewith and longitudinal movement thereof and controlling the movements of the pinion, said pinion and screw member having a compression space between them, and a coiled driving spring interposed between such pinion and member and connected therewith respectively.
- 35 24. A drive for engine starters comprising a rotatable screw shaft, a pinion also capable of rotary and longitudinal movements, a screw member screw-threaded on the shaft for rotary movement therewith and longitudinal movement thereof and controlling the movements of the pinion, said pinion and member having a compression space between them, means for covering such space, and a coiled driving spring interposed between such pinion and member and connected therewith respectively.
- 40 25. A drive for engine starters comprising a rotatable screw shaft, a pinion also capable of rotary and longitudinal movements, a screw member screw-threaded on the shaft for rotary movement therewith and longitudinal movement thereof and controlling the movements of the pinion, said pinion and member having a compression space between them, a sleeve cooperating with the member and pinion to cover said space, and a coiled driving spring interposed between such pinion and member and connected therewith respectively.
- 45 26. A drive for engine starters comprising a rotatable screw shaft, a pinion also capable of rotary and longitudinal movements, a screw member screw-threaded thereon for rotary movement therewith and longitudinal movement thereof and controlling the movements of the pinion, said pinion and member having hubs or extensions at their adjacent ends but separated to form a compression space, and a coiled driving spring surrounding such hubs and connected with the pinion and member respectively.
- 50 27. A drive for engine starters comprising a rotatable screw shaft, a pinion also capable of rotary and longitudinal movements, a screw member screw-threaded thereon for rotary movement therewith and longitudinal movement thereof and controlling the movements of the pinion, a coiled driving spring interposed between such member and pinion, and studs on the same sides of the head and pinion for anchoring the spring thereto.
- 55 28. A drive for engine starters comprising a rotatable screw shaft, a pinion also capable of rotary and longitudinal movements, a screw member screw-threaded thereon for rotary movement therewith and longitudinal movement thereof and controlling the movements of the pinion, said pinion being overbalanced on one side, and driving means between the pinion and member.
- 60 29. A drive for engine starters comprising a rotatable screw shaft, a pinion also capable of rotary and longitudinal movements, a screw member screw-threaded thereon for rotary movement therewith and longitudinal movement thereof and controlling the movements of the pinion, said pinion having on one side a projecting portion to overweight it on that side, and driving means between the pinion and member.
- 65 30. A drive for engine starters comprising a rotatable screw shaft, a pinion also capable of rotary and longitudinal movements, a screw member screw-threaded thereon for rotary movement therewith and longitudinal movement thereof and controlling the movements of the pinion, said pinion having on one side a projecting portion to overweight it on that side, and a coiled driving spring anchored to said projecting portion and the screw member respectively.
- 70 31. A drive for engine starters comprising a rotatable screw shaft, a screw member screw-threaded thereon for rotary movement therewith and longitudinal movement thereof, a pinion surrounding the shaft and in axial alinement with said member and a torsion spring driving connection between the member and pinion.
- 75 32. In apparatus of the class described, in combination, an engine, a motor for starting

the same, a driven member connected with said engine, a driving member normally out of cooperation therewith, a shaft rotated by said motor, a nut threaded on said shaft and a yieldable member interposed between said nut and said driving member.

33. In a starter for gas engines and the like, comprising in combination with a driven member operatively connected with the engine, a driving member adapted to cooperate with and drive the other member but normally out of cooperation therewith, a shaft driven by a starting motor, said driving member being mounted on said shaft, shifting means for said driving member, and means on said shaft for causing a longitudinal movement of said shifting means, to effect movement of said driving member into cooperation with said driven member.

34. A starter for gas engines and the like comprising in combination a driven member operatively connected with the engine a driving member adapted to cooperate with and drive the other member but normally out of cooperation therewith, shifting means for said driving member operated by a starting motor and means for limiting the range of said shifting means and for connecting said motor in driving relation with said driving means.

35. A starter for gas engines and the like comprising in combination a driven member operatively connected with the engine, a driving member adapted to cooperate with and drive the other member but normally out of cooperation therewith, shifting means for said driving member operated by a starting motor, said shifting means including a relatively rigid member, a shaft having a portion inclined to its axis and rotating with said motor and cooperating with said rigid member and torque transmitting means including said rigid member and operative after said shifting means has performed its function.

36. In apparatus of the class described, in combination, an engine, a motor for starting the same, a driven member connected with said engine, a driving member normally out of cooperation therewith, shifting means for said driving member, including a rigid element, a spring member connecting the latter element with said driving member, and means connected with the motor for imparting substantially translational movement to said rigid member.

37. In apparatus of the class described, in combination, an engine driven gear, a driving gear adapted to cooperate therewith, means rendered effective by a starting motor for moving said driving gear into mesh with said driven gear, including a screw shaft driven by said starting motor, a nut on said shaft and means movable with said nut and

connected to said driving gear to transmit torque, and means to secure the nut to the screw shaft after the gears are in mesh.

38. In a starting device, the combination of, an engine driven member having gear teeth thereon, a driving shaft having screw threads, a nut carried on said threads, a gear wheel slidably supported on said shaft adjacent the engine driven member and adapted to engage the gear teeth thereon and means drivingly connecting said nut to said gear wheel for the purpose described.

39. In apparatus of the class described, in combination with a member connected with an engine to be started, a driving shaft, a driving member slidably carried on said shaft and normally out of cooperation with the engine member, a nut threaded on said shaft in longitudinal alinement with the said driving member and a single yieldable member interposed between said nut and said driving member, said yieldable member serving as one of its functions to hold the driving member in normal, spaced relationship with the nut.

40. In apparatus of the class described, in combination, a motor for starting the same, a driving member normally out of cooperation with but adapted to engage a member of the engine to be started, shifting means separate from the driving member and mounted to move longitudinally and to cooperate with the driving member to shift the latter into engagement with the engine member, and a part inclined to the axis of said motor between said motor and said shifting means and adapted to actuate said means.

41. In apparatus of the class described, a rotatable shaft, a driving member and shifting means separate from the driving member and mounted on the shaft for longitudinal movement thereof and rotary movement therewith and operatively connected to the driving member to impart its said movements thereto.

42. A drive for engine starters comprising a rotatable shaft, a driving member mounted thereon and adapted to cooperate with and drive a member of the engine to be started, and a control member mounted on such shaft for longitudinal movement thereof and rotary movement therewith, and operatively connected with the driving member to impart its movements thereto.

43. A drive for engine starters comprising a rotatable shaft, a driving member mounted thereon and adapted to cooperate with and drive a member of the engine to be started, a control member mounted on such shaft for longitudinal movement thereof and rotary movement therewith, and a yielding driving connection between such members.
